UNITED STATES PATENT OFFICE.

ROGER TATHAM, OF ROCHDALE, COUNTY OF LANCASTER, ENGLAND.

COILER FOR CARDING-MACHINES, &c.

SPECIFICATION forming part of Letters Patent No. 271,155, dated January 23, 1883.

Application filed December 30, 1881. (No model.) Patented in England April 18, 1879, No. 1,532, and in Germany May 23, 1881, No. 21,805.

To all whom it may concern:

Be it known that I, ROGER TATHAM, of Rochdale, in the county of Lancaster, England, mechanical engineer, have invented certain improvements in Coilers for Carding-Machines, &c., of which the following is a specification, reference being had to the accompanying drawings.

My invention relates more particularly to 10 that apparatus used in conjunction with carding-machines, railway-heads, drawing-frames, &c., which is commonly called the "coiler," but is also applicable to other cans or receptacles for receiving the fibrous material. The 15 cans in coilers have been mounted on a plate which has a partial or intermittent rotation imparted to it for the purpose of changing the cans; but according to my invention the cans are mounted upon rotary can-plates, which are 20 carried by a frame or carriage which is mounted in ways or tracks, and has a rectilinear movement imparted to it alternately in opposite directions to remove a full can from under the head of the coiler and bring an empty can into 25 the same position to be filled.

My invention therefore consists in the combination, in a coiler, with tracks or ways, of a frame or carriage supported on the same rotary can-plates carried by the said frame or 30 carriage, mechanism for moving or reciprocating said frame or carriage in opposite directions, and mechanism for rotating said can-plates when they are brought under the head of the coiler.

The invention also consists in the particular mechanism hereinafter described for reciprocating the frame or carriage.

The invention also consists in the combination, with the aforesaid frame or platform, of 40 calender-rollers in the head of the coiler and driving mechanism therefor; devices for engaging and disengaging their driving mechanism, adapted to be operated by the frame or carriage in its rectilinear movements, and a 45 knife or cutter carried by the frame or carriage for cutting the sliver as the frame or carriage is moved and while the calender-rollers are stopped.

In the accompanying drawings, Figure 1 is 50 a front elevation of a coiler with my apparatus attached. Fig. 2 is a side elevation of the

parts represented in Fig. 1, both these figures being shown broken for convenience of illustration. Fig. 3 is a horizontal section taken on the line A B, Fig. 1. Fig. 4 represents a 55 vertical section of the lower part of the machine, the reciprocating frame or carriage and its tracks or ways being omitted. Fig. 5 represents a front view of a portion of the mechanism for reciprocating the frame or carriage; 60 and Fig. 6 represents a partly-sectional side view of the parts shown in Fig. 5, the same letters of reference being applied to corresponding parts throughout the whole series of figures. 65

At 1 is a base-plate, upon which is mounted a square pillar, 2, carrying at its top the coiler-head 3. Within the pillar 2 is the usual upright shaft, 4, which receives rotatory motion through the bevel-wheel 5, gearing into another 70 bevel-wheel, 6, mounted upon one end of a shaft, 7, turning in a bracket, 8, carried by the pillar 2. Upon the shaft 7 is a toothed wheel, 9, gearing into any suitable wheel of the carding-engine or other machine in conjunction 75 with which the coiler is being used. Upon the lower end of the upright shaft 4 is mounted, fast thereon, a pinion, 10, (shown in detached view, Fig. 4,) gearing into a wheel, 11, turning loosely upon a stud, 12, fast with the base-plate 1:

Attached to the wheel 11, and turning therewith, is a pinion, 13, gearing into a wheel, 14, turning loosely upon the upright shaft 4.

Fast with the wheel 14, but turning loosely 85 upon the upright shaft 4, is a pinion, 15, gearing into the wheel 16, turning upon a stud, 17, fixed in the base-plate 1. By means of this wheel 16 the rotary motion of the can-plates 18 19 is produced. 90

Within the base-plate 1 are formed grooves 20 20*. Upon these grooves a frame or carriage, 21, is mounted so as to be capable of sliding thereon, such frame or carriage being provided with ribs or strips which slide in the 95 grooves 20 20*.

Into the frame 21 are screwed studs 22 22*, upon which are mounted, so as to be capable of turning thereon, the can-plates 18 19, so arranged that when the frame 21 is slid upon the grooves 20 20*, as will hereinafter be described, either of the wheels 18* 19*, provided

or formed upon the under side of the can-plates 18 19, may be brought into gear with the wheel 16, by which they will then be driven.

Attached to the ends of the frame 21, and extending therefrom, are arms 23 23*, to which are bolted toothed racks 24 25. Into one or other of these racks a pinion, 26, is caused periodically to engage, as I will hereinafter de-
10 scribe, for the purpose of traversing the frame 21 longitudinally upon the grooves 20 20* formed within the base-plate 1.

Fast upon the upright shaft 4 is mounted a worm, 27, taking into the teeth of a worm-wheel, 28, mounted fast upon a short-shaft, 29, capable of turning within a bracket, 30, carried by the pillar.

Fast upon the shaft 29 is a bevel-pinion, 31, gearing into another bevel-pinion, 32, fast upon 20 a short upright shaft, 33, carried by an arm of the bracket 30.

Fast upon the shaft 33 is a worm, 34, gearing into the teeth of a mutilated wheel, 35, mounted so as to turn loosely upon a shaft, 36, 25 being retained thereon by means of a set-loom, 37. The shaft 36 revolves within the bracket 38, by which it is supported, such bracket being secured to the pillar 2.

Upon the face of the mutilated wheel 35 is 30 fixed a stud, 39. (More clearly seen in the detached views, Figs. 5 and 6.)

Upon the stud 39 is mounted, so as to be capable of turning thereon, a pinion, 26, gearing into another pinion, 40, mounted upon the 35 shaft 36.

Fast upon the upright shaft 4 is a bevel-pinion, 41, gearing into another bevel-wheel, 42, fast upon the shaft 36. As the shaft 4 revolves rotary motion is communicated through 40 the wheels 41 42, shaft 36, and pinion 40 to the pinion 26, which will be rotated in the direction of the arrow thereon.

In the position of the parts as shown in the drawings the material is being delivered and 45 coiled in the usual manner within the can 43 or other receptacle supported by the can-plate 18, as in Figs. 2 and 4, the empty can to be next filled being supposed to be placed upon the can-plate 19. The cans are omitted in the 50 other figures to avoid confusion of lines. As the upright shaft 4 revolves a slow rotatory motion will be imparted to the mutilated wheel 35, in the direction of the arrow placed thereon in Fig. 5, by the worm 27 by means of the 55 worm-wheel 28, bevel-pinions 31 32, shaft 33, and worm 34. Such motion will bring the pinion 26 into position for gearing with the rack 25, but immediately before doing so one of the spaces *c* in the mutilated wheel 35 will have 60 arrived opposite the worm 34, and the wheel 35 will therefore cease to be driven thereby. The mutilated wheel 35 being mounted loose upon the shaft 36, which is revolving in the direction of the arrow shown in the pinion 40 65 in Fig. 5, will cause a further rotation of the mutilated wheel 35 in the same direction, such rotation bringing the pinion 26 into gear with

the rack 25, and also the set of teeth *E* of the mutilated wheel 35 into gear with the worm 34, which, then acting as an abutment, will 70 thereby cause the pinion 26 to draw the rack 25 in the direction of the arrow thereon, thereby causing the frame 21, carrying the can-plates 18 19, to be also traversed along the grooves formed in the base-plate 1, thereby 75 bringing the empty can upon the can-plate 19 into the position previously occupied by the one filled. When the rack 25 has been traversed a certain distance a blank portion thereof, 25*, (see Fig. 1,) will have arrived under 80 the pinion 26. The rack will then be no longer acted upon by the said pinion. The above-described movements will have brought the empty can or other similar receptacle on the plates 19 into position for being filled. The 85 one filled may now be removed and an empty one substituted therefor, to be in its turn filled with material. The mutilated wheel 35, having been again brought into gear with the worm 34, will continue to be slowly rotated 90

thereby in the direction of the arrow on the wheel 35 until the pinion 26 will be brought nearly into gear with the rack 24. At the same time the blank space *D* on the mutilated wheel 35 will have arrived opposite the worm 34, and 95 the mutilated wheel 35 will be again carried forward in the direction of its arrow by the rotation of the shaft 36, thereby bringing the pinion 26 into gear with the rack 24, as previously described in reference to the rack 25, and will cause the rack 24 to be traversed in the direction of the arrow thereon until the blank portion 24* of the rack 24 arrives above the pinion 26, when the rack will be no longer acted upon thereby. This movement of the 100 rack 24 will have carried with it the frame 21 and the can or other receptacle upon the can-plate 18 into position for being filled. At each end of the base-plate 1 are projecting parts 44 44, which serve as stops against which 105 the frame 21 arrives after it has been traversed in one direction or the other by the pinion 26. In order to effect a severance of the sliver when the can or other receptacle is being 110 changed, I mount an upright rod, 45, upon the frame or carriage 21. Upon the upper end of this rod and close under the coiler head I fix a cross-plate or blade, 46, extending across the path in which the sliver is delivered into the can or other receptacle. The edges of the 115 blades or cross-plate 46, I form serrated to insure a severance of the sliver, as will herein-after be described.

Upon the sliding frame 21, I form a projecting part, 47, (see Figs. 1 and 3,) provided with 120 inclines leading to raised portions 48 49 at each end thereof. Resting upon the part 49 is the lower end of a rod, 50, which passes through a guide, 51, attached to the pillar 2. The upper end of the rod 50 passes through 125 an aperture formed in the coiler-head, which acts as a guide. To the upper end of the rod 50 is attached a forked part, 52, embracing a groove formed in the boss of a bevel-wheel,

53, mounted so as to be capable of sliding up-
on the upright shaft 4, by which it is driven
through the medium of a slot and key. The
bevel-wheel 53 gears into a bevel-pinion, 54,
5 fast upon the axle of one of the usual calender-
rollers, 55, by which the material is delivered
to the press-wheel plate 56. When the parts
are in the position shown in the drawings the
calender-roller 55 will receive rotatory motion
10 from the shaft 4; but when the frame 21 is
being traversed for the purpose of changing
the cans or other receptacles, as previously de-
scribed, the raised part 49 will be removed
15 from beneath the rod 50, which, being no longer
supported, will, by its own weight and by means
of the forked part 52, attached to the rod 50,
withdraw the bevel-wheel 53 out of gear with
the bevel-pinion 54, thereby arresting the motion
20 of the calender-rollers. During the time
the calender-rollers are stopped the serrated
plate or blade 46 passes underneath the press-
wheel plate 56, and, coming in contact with
the sliver which is held by the calender-rollers,
will sever it. A continued traversing of the
25 frame 21 will bring the raised part 48 under
the lower end of the rod 50, which will cause
the bevel-wheels 53 54 to pass into gear for
the delivery of the sliver. When the frame
30 21 is again traversed in an opposite direction
the rotary motion of the calender-rollers 55
will be again arrested when the depressed
part between the two raised portions 48 49 is
35 passing beneath the lower end of the rod 50,
when a severance of the sliver will again take
place.

Although I have hitherto referred to the
changing of the cans of a single coiler only, it
will be readily understood that by extending
the sliding frame 21 my invention may be ap-
plied to a series of coilers, such as would be
40 used in a drawing-frame.

Having thus described my invention and
the manner of carrying it into effect, I desire
it to be understood that I claim—

1. The combination, in a coiler, with tracks 45
or ways, of a frame or carriage supported
thereon, rotary can-plates carried by the said
frame or carriage, mechanism for moving or
reciprocating said frame or carriage alter-
nately in opposite directions, and mechanism 50
for rotating said can-plates when they are
brought under the head of the coiler, substan-
tially as herein described.

2. The combination, in a coiler, with tracks
or ways, of a frame or carriage supported 55
thereon, rotary can-plates carried by said frame
or carriage, mechanism for moving or recipro-
cating said frame or carriage alternately in
opposite directions, mechanism for rotating
said can-plates when they are brought under 60
the head of the coiler, calender-rollers, be-
tween which the sliver passes, driving mech-
anism for said rollers, adapted to be disen-
gaged from said rollers by the movement of
said frame or carriage, and a knife for cutting 65
off the sliver carried by said frame or carriage,
substantially as herein described.

3. The combination of the tracks or ways 20,
the frame or carriage 21, the can-plates 18 19,
provided with wheels 18* 19*, the racks 24 25, 70
attached to said carriage, the shaft 4, gearing
for connecting said shaft with either of the
wheels 18* or 19*, the shaft 36, the mutilated
wheel 35, mounted loosely on said shaft, the
pinion 40 on the shaft 36, the pinion 26, car- 75
ried by said wheel 35, gearing for transmitting
a slow motion to the mutilated wheel 35 from
the shaft 4, and gearing for transmitting a
quicker motion to the shaft 36 from said shaft
4, all substantially as herein described.

ROGER TATHAM.
